3,112,808 BALANCE BEAM

Lloyd B. Macurdy, Silver Spring, Md., assignor to the United States of America as represented by the Secretary of Commerce

Filed Mar. 1, 1962, Ser. No. 176,835
3 Claims. (Cl. 177—261)

This invention relates to balance beams, and more particularly relates to a balance beam incorporating improved mountings for the knives.

In the construction of a balance beam for use in a precision balance, a center knife and either one end knife (in the case of a single pan balance) or a pair of end knives (in the case of an equal arm balance) must be mounted thereon such that (1) the edge of each end knife is parallel with respect to the edge of the center knife, and (2) the edges of the end knives are at predetermined distances from a horizontal reference plane that includes the edge of the center knife.

Various means have been devised for mounting knives on a balance beam. In general, the means that are mechanically simple and economical, such as screws, cement, swaging, etc., do not provide accurate, stable alignment of the knife edges; while the means that provide accurate alignment involve a multiplicity of wedges, clamps, shims, and holders, and consequently are complex, heavy, and costly.

In accordance with the present invention, a balance beam is provided with a transverse channel for each knife. The bottom of the channel for the center knife is made planar with the plane thereof parallel to the desired horizontal reference plane taken through the edge of the center knife. The center knife is mounted in such channel with its base on the planar bottom of the channel and is clamped therein by means which permit the knife to be shifted and/or rotated with respect to the planar bottom. Since the edge of the center knife is parallel to the base, the edge remains in the horizontal reference plane as the knife is shifted and rotated on its planar seat.

The bottom of the channel for the end knife is also made planar, but the plane of this planar seat is inclined from the horizontal reference plane, as measured along the length of the beam. The end knife is also clamped by means that permit the knife to be shifted and rotated with respect to the seat. Since the seat is inclined, rotation of the knife thereon enables either end of the knife to be raised or lowered so as to position the edge thereof parallel to or within the horizontal reference plane. Shifting of the end knife on such inclined seat permits the edge of the knife to be positioned at the desired distance from the horizontal reference plane containing the edge of the center knife. After the end knife is so positioned, the center knife may be positioned so that the edge of the center knife is parallel to the edge of the end knife. Thus, the present invention provides accurate, stable alignment of the knife edges with a minimum of parts.

The present invention therefore has as an object to provide improved means for accurately mounting knives on a balance beam.

It is another object to mount knives on a beam by means which involve a minimum number of parts.

Another object is to provide a beam having means for mounting knives thereon in a manner which is simple, economical, and stable during use.

It is a further object of the invention to provide a beam having seats for knives in which at least one of the seats is inclined from the horizontal reference plane that includes the center knife edge.

Other objects and features of the invention will become apparent to those skilled in the art as the disclosure is made in the following detailed description of a preferred

2

embodiment of the drawing as illustrated in the accompanying set of drawings, in which:

FIG. 1 is a front elevation of the balance beam embodying the present invention;

FIG. 2 is a cross section view taken along the line 2—2 of FIG. 1, looking in the direction of the arrows.

The exemplary embodiment of the invention shown in FIG. 1 comprises a beam 10 provided at one end with a counterweight 11, whereby the beam is suitable for use in a single pan balance. A transverse channel 12 is formed in the central underside of the beam and a transverse channel 14 is formed in the topside of the beam at the end opposite counterweight 11.

The bottom surfaces 16, 18 of the channels 12, 14 are planar and thus are seats that receive the bases 24, 34 of the center and end knives 20, 30 respectively. The upper sides 19 of the channels 12, 14 slope outward, thereby providing V-shaped spaces in conjunction with the tapered sides 21, 31 of the knives 20, 30. The V-shaped spaces receive semicylindrical wedges 40, which serve to adjustably clamp knives 20, 30 in place.

It will readily be appreciated that a channel side 19 in conjunction with a knife side (21, 31) defines two intersecting planes, the line of intersection of which varies as the distance between the knife and channel side is varied. For example, as the distance between the knife and channel side increases, the line of intersection of the two planes is lowered and shifted away from the channel side 19. In addition, if one end of the knife is moved farther from the channel side than the other end is moved, the line of intersection tilts lower near the knife end that was moved farther. Thus, shifting and rotating the knives 20, 30 on their seats causes the line of intersection of the planes defined by the V-shaped spaces between the knife sides 21, 31 and the channel sides 19 to vary.

It will also be readily appreciated that the cylindrical surfaces of the wedges 40 tangentially contact the planes defined by the V-shaped spaces, with the axis of the cylinder parallel to the line of intersection of the planes. Consequently, it is clear that the two wedges 40 associated with a knife (20, 30) can retain the knife against the seat (16, 18) in any position associated with the shift and/or rotation of the knife relative to the seat.

To tighten the wedges 40, bolts 50 are provided as shown in FIG. 2. The bolts 50 pass through holes provided in the wedges and further pass through holes drilled into the beam 10, so as to thread into swivel nuts 52, disposed in transverse bores provided in beam 10. The swivel nuts 52 permit the cylindrical axes of the semicylindrical wedges 40 to align parallel with the line of intersection of the intersecting planes defined by the channel side 19 and knife side (21, 31) as bolts 52 are tightened.

In practice, the bolts 50 in conjunction with wedges 40 not only clamp the knives 20, 30 in position, but serve as means for micrometrically positioning the knives, inasmuch as the tightening of a bolt 50 causes that end of the wedge 40 therebeneath to penetrate into the V-shaped space between the sloping channel side 19 and sloping knife side (21, 31), thereby tending to move the adjacent end of the knife away from the channel side 19. It is of course necessary that one or both of the bolts 50 associated with the wedge 40 disposed on the opposite side of the knife be loosened so that the knife may shift.

In accordance with the present invention, the plane of seat 16 associated with center knife 20 is made parallel to the horizontal reference plane that includes line P—P and extends normal to the plane of FIG. 1. The center knife 20 is formed so that the edge 22 is parallel to the base 24. Consequently, the knife 20 may be shifted and rotated on the seat 16, and the edge 22 will remain in the horizontal reference plane represented by line P—P.

The seat 18 provided for the end knife 30 is also planar, but the plane thereof is slightly inclined from the horizontal reference plane with the line of intersection of said planes being substantially normal to the vertical plane of symmetry of beam 10. The angle of inclination α preferably is in the order of a few degrees. Since the seat 18 is inclined, rotation of the end knife 30 thereon by means of the wedges 40 as described above permits the ends of edge 32 of the knife 30 to be brought into position parallel with the horizontal reference plane that includes line P—P. The knife 30 may then be shifted up or down the inclined seat 18 until the edge 32 is at the desired distance from the horizontal reference plane.

After the end knife 30 is adjusted in the manner just described, the center knife 20 is rotated if necessary until its edge 22 is parallel with the edge 32 of the end knife 30. Then the center knife is shifted so as to adjust the distance between its edge 22 and the edge 32 of end knife 30, whereby the knives are in completed position.

In FIG. 1, the center seat 16 is formed such that its plane is horizontal, while the plane of end seat 18 is inclined from the horizontal as measured along the length of beam 10. It will be appreciated that the relationship could be reversed with end seat 18 being horizontal and center seat 16 inclined. It is also evident that the inclined seat 18, shown as sloping downward from right to left, could slope downward in the reverse direction from left to right, as measured along the length of beam 10.

In the embodiment shown in FIGS. 1 and 2, the beam 10 is for use in a single pan balance and is provided at one end with a counterweight 11. Consequently, the beam 10 has only one end knife 30. In the case of a beam for use in a two-pan (equal arm) balance, the beam would be provided with two end knives. In such a beam, the present invention may be practiced in several ways. Any one of the three seats for the three knives could be inclined, while the other two are made horizontal. Alternatively, the seats for the end knives may be both inclined, and the center seat may be horizontal. In the latter embodiment, the end knives are shifted on their seats to secure the desired distance between their edges and the horizontal reference plane passing through the edge of the center knife. The center knife is then shifted on its horizontal seat to achieve equality of the arm lengths.

While the knives 20, 30 have been illustrated as adjustably clamped to their respective seats by means of wedges 40, which are preferred because they provide a means

for accurately positioning the knives in addition to clamping same, it will be appreciated that alternative adjustable clamping means may be employed within the scope of the invention. For example, each of the knives could be clamped to the beam by providing a threaded hole in the base of the knife, so as to receive a bolt disposed in an oversize hole drilled through the beam in the center of the seat, whereby the knife may be shifted and/or rotated as permitted by the oversize hole surrounding the bolt. Tightening of the bolt into the threaded base of the knife would of course draw the knife into snug engagement with the seat and thereby lock the position of the knife.

The invention has been shown and described in a single preferred form and by way of example, and obviously many variations and modifications may be made therein without departing from the spirit of the invention. It is to be understood, therefore, that the invention is not to be limited to any specific form or embodiment except 20 insofar as such limitations are specified in the appendent claims.

What is claimed is:

1. In a balance, the combination of a horizontal beam having a planar center seat and at least one planar end seat, the plane of one of said seats being horizontal, and the plane of the other of said seats being inclined from the horizontal as measured along the length of said beam, at least two movable knives, and means for adjustably clamping said knives to said seats.
2. The combination set forth in claim 1, wherein said seats are the bottoms of transverse channels in said beam.
3. The combination set forth in claim 2, wherein said channels have sides which slope outwardly, said clamping means comprising semicylindrical wedges disposed between said channel sides and the adjacent sides of said knives, said wedges being vertically and laterally adjustable, whereby said knives may be shifted and rotated with respect to said seats.
